UNITED STATES PATENT OFFICE.

RAY H. GROVES, OF PORTLAND, OREGON, ASSIGNOR TO BONNIE J. GROVES, OF PORTLAND, OREGON.

BUILDING BLOCKS.

Application filed July 31, 1923. Serial No. 654,801.

To all whom it may concern:

Be it known that I, RAY H. GROVES, a citizen of the United States, residing at Portland, in the county of Multnomah and 5 State of Oregon, have invented new and useful Building Blocks, of which the following is a specification.

My invention relates to improvements in building blocks for movable toys, in the 10 construction of which wheels, shafts and interlocking blocks are used.

The objects of my invention are to furnish a toy which develops the constructive ability of children, which lends itself to the production of a large variety of structures of 15 pleasing appearance, and in which the structures are of sufficiently rigidity to permit a certain amount of handling.

I attain these objects with the mechanism 20 illustrated in the accompanying drawing, in which—

Fig. 1 is a long block with two notches in each long edge.

Fig. 2 is a short block with one notch in 25 two opposite edges.

Fig. 3 is a block similar to Fig. 1, but provided with two holes.

Fig. 4 represents a shaft or an axle.

Fig. 5 is a narrow block with especially 30 wide notches in one edge.

Fig. 6 may be designated as a tie block.

Fig. 7 is a short block having one notch and one hole.

Fig. 8 is a wheel.

Fig. 9 represents a dump car—one of the 35 many varieties of structures in which the above named elements are employed.

Similar numerals refer to similar parts throughout the several views.

The blocks 1 are made in different lengths 40 and interlocked to form structures, similar to Fig. 9, in a manner well known in the art. The blocks 2 are employed for columns in suitable places, as, for instance, to border the sides of openings in a wall. But to give 45 these structures their distinctive aspect and quality, the structural members depicted in Figs. 3 to 8 have been designed and combined with the blocks 1 and 2 in various 50 ways. Perhaps the chief distinction is attained by the employment of the wheels 3,

which are pressed onto the tapering ends of the shaft 4, and used either as medium of propulsion, or otherwise to simulate a steering wheel as shown in Fig. 9. To 55 provide bearings for the shafts 4, the blocks 5 are furnished with holes 6. The shafts 4 and blocks 5 may also be used to construct the tilting hopper of a dump car, however, in such a case the blocks 7 must be added to 60 furnish a support for the shaft 4. The blocks 8 are chiefly utilized to hold the boards which constitute the floor or the roof in alignment. For this purpose the projections 9 on the boards 8 enter the spaces 65 created by the notches of two adjoining boards, while the recesses 10 in the boards 8 furnish a seat for that portion of the block 1 which is reduced by the two notches on opposite edges. The tie block 11 holds two 70 superimposed members in alignment where one of the members should happen to be without a notch, as instanced by the tie block shown in the driver's seat 12 in Fig. 9. Here the side 13 of the seat interlocks with the 75 notches 14 in member 11, but the edge of the underlying member has no notch. Yet, the seat will be prevented from shifting laterally by the raised back 15 of the tie block 11 which is wedged between the walls of the 80 vehicle.

Having thus described my invention, I claim:

A toy of the character described, formed from flat, rectangular structural members, 85 having transverse notches in their edges, certain of said members having perforations near one edge, cylindrical structural members adapted to be inserted in said perforations, wheel-shaped structural members 90 adapted to be pressed on the ends of certain of the cylindrical members, certain of the flat rectangular structural members having perforations near one end to receive the ends of certain of said cylindrical members, 95 whereby said structural members may be assembled to form a toy of the character shown in Fig. 9.

Signed by me at Portland, Oregon, this 26th day of July, 1923.

RAY H. GROVES.
